PARTITION

Harry A. Waldman, Long Island City, N. Y.

Application November 10, 1931, Serial No. 574,056

8 Claims. (Cl. 20—4)

My invention relates to improvements in partitions which are set up by constructing a skeleton frame with openings to accommodate panels or sections of more or less uniform dimensions, the 5 sections being interchangeable so that alterations in the assembly may be made without destroying any of the parts and without dismantling the skeleton frame.

This invention has for its object to provide a 10 partition of this character which is erected about a skeleton frame embodying in its construction a series of connecting rods extending longitudinally throughout the frame, the rods being capable of being loosened up to allow alterations to be made, then tightened up again to bring the 15 entire structure into a single rigid unit, and during maintenance to tighten the partition by taking up the loose joints.

A further object of my invention resides in 20 the particular means utilized to allow one type of panel or section, door or transom to be interchanged for another type without disturbing or dismantling any part of the partition except just where the change or changes are being made.

25 Another object of my invention is directed to the construction and arrangement of separate base boards for each section of the partition, the utility of separate base boards being in the fact that when it is necessary to interchange a fixed 30 panel for a door, only the base board in the section accommodating the door need be removed to open the space clear to the floor.

I accomplish these objects by means of the construction and arrangement of parts described 35 in the specification, set forth in the appended claims and illustratively exemplified in the accompanying drawings, in which:

Figure 1 is a perspective view of a partition in the course of construction;

40 Figure 2 is a front elevational view of a section of partition as it appears when complete;

Figure 3 is a substantially vertical sectional view taken on lines 3—3 of Figure 2 showing a panel and fixed overhead sash;

45 Figure 4 is a similar section of the upper portion of the partition taken on lines 4—4 of Figure 2 and illustrating a door and pivoted transom;

Figure 5 is a substantially transverse sectional view taken on lines 5—5 of Figure 2 and showing the post, panel and door;

50 Figure 6 is a similar view taken on lines 6—6 of Figure 2 above the cross piece showing a fixed sash and pivoted transom;

Figure 7 is a sectional view on lines 7—7 of 55 Figure 2 showing the removable base;

Figure 8 is a substantially transverse sectional view of the partition having dividing and corner sections projecting at right angles from the original line;

Figure 9 is a transverse sectional view taken on lines 9—9 of Figure 2 showing the removable base and posts;

Figure 10 is another substantially transverse sectional view of the partition taken on lines 10—10 of Figure 2 showing the metal tie rods;

Figures 11 and 12 are perspective views of a section of a post and adjacent portion of a removable base respectively, each being provided with a portion of the means for locking the parts together;

Figure 13 is a front elevational view of a portion of a bank screen;

Figure 14 is a substantially vertical sectional view of the screen taken on lines 14—14 of Figure 13;

Figure 15 is a sectional view of a portion of my improved partition illustrating the use of extension units which may be added to accommodate high ceiling conditions;

Figure 16 is a sectional view showing the arrangement of a header at the corner installation of a partition;

Figure 17 is an end elevational view of a post equipped to accommodate an extension piece;

Figure 18 is a sectional view showing the end of the tie rod anchored in a wall of stone, brick or other solid material;

Figure 19 is a sectional view similar to that illustrated in Figure 18 except that a different type of fastening means is used in the wall; and

Figure 20 is a substantially transverse sectional view of a post showing spring retaining means for releasably holding the side moulding in place.

Referring to the drawings and particularly to Figure 1, 10 denotes the floor strip which is fixed upon the floor along the line of the partition. Mounted upon the floor strip in upright position and uniformly spaced from each other, are a series of pilasters or posts 11. A cornice 12 is mounted upon the upper ends of the posts 11 and

40 consists of a center header piece 13 and side crown moulding strips 14, the under face of the header piece 13 being provided with a longitudinally disposed channel 15, illustrated particularly in Figures 3 and 4. If the ceiling proper is actually higher than the cornice 12, a filler strip 16 is

45 mounted upon the header piece 13 and projected upwardly to meet the ceiling surface. The filler strip 16 is utilized to give the appearance of a beam and comprises spaced parallel upright filler

boards 16', the latter being mounted upon an intermediate frame 16". The lower end of the filler strip 16 rests in a groove 13' in the upper face of the header 13, one side of the groove 13' being formed by a removable moulding strip 13". The upper end of the filler strip 16 is held in position with respect to the ceiling proper by means of moulding strips 16" which attach to the ceiling and embrace opposite sides of the filler strip. In each space between posts 11 there is a cross piece or lower header strip 17 which is arranged parallel to and spaced somewhat below the upper header 13 and which consists of a length of wood, preferably square in transverse section, having a longitudinal bore 18 extending throughout its entire length and being further provided with a channel 19 along its under face. Normally each pilaster or post comprises a wood strip which is substantially square in transverse section and along the sides facing inwardly there is a fixed or removable moulding 20 adjacent one corner. In order to establish a proper connection at the meeting ends of the lower header 17 and posts 11 and between the upper ends of the posts and the upper header 13, the latter is morticed to receive the tongue of the post in the one instance and in the other instance, the posts are morticed to receive the tongues at the ends of the lower header.

At the lower ends of the posts 11, the latter are enlarged with base blocks 11' to form the line of the base board and in each post, opposite the moulding 20, there is a removable moulding 21 which together with the moulding 20, meet the ends of the blocks 11' and form a channel 22 rising from the floor strip 10 to the bottom line of the lower header piece 17. As already mentioned, the base boards in this invention comprise a series of separate members 23, each there-of being of a length to fit closely between adjacent posts 11 and having tongues 24 at its opposite ends to be received in the channels 22 of the posts. The under side of the base board 23 is provided with a stepped channel 25, the outer section being adapted to closely embrace the upper sides of the floor strip 10 while the inner section forms a part of an open channel to accommodate an electric cable. The upper side of the base board section 23 is arranged with a channel 26 to register with the channel 22 in the posts formed by the single mouldings 20 before assembly and by the second separable moulding strips 21 installed after assembly, as hereinafter described.

In order to accommodate the cables usually installed in partitions for electrical connections, the posts 11 are each provided with a longitudinal bore 28. Each post 11 is further provided with a transverse bore 29 which registers with the bores 18 of the cross pieces 17.

Referring now to the means used to firmly tie the skeleton frame together, 30 denotes a section of rod which is arranged in the bore 18 and is of a length slightly longer than the length of a cross piece 17, the rod being threaded at opposite ends to accommodate a union or nipple 31, the shank end of which projects into a counter bore 32 at the end of the bore 18. The nipple 31 is provided with a flange 33 at one end which is accommodated in a counter-sunk portion 34 of the bore 29 in the post. When making an assembly, only alternate cross pieces 17 receive the full length rods 30, the intermediate cross pieces 17 carrying shorter rods 35 which screw into the shank ends of the nipples, the outer end of each short rod

35 projecting through the bore 18 and into a slot 36 cut into an outer face of the cross strip 17 to meet the bore thereof. The threaded end protruding into the slot 36 is provided with a washer 37 and nut 38 which when tightened draws the two adjacent cross pieces and intermediate post very tightly together. It will be seen that when succeeding units are assembled and brought together in this manner, the frame is easily loosened and tightened to provide a continuous strengthening device throughout the entire length of the partition.

The end rods may be either long or short sections 30 and 35 respectively, and solidly anchored in a wall of brick or hollow tile as illustratively exemplified in Figure 18.

The spaces between the upright posts as previously stated are adapted to accommodate fixed panels 39 or doors 40 below the cross piece 17 and fixed lights 41 or movable transoms 42 above the cross piece. In the space adapted to receive a panel 39, the frame consists of the posts 11 on the upright sides with their mouldings 20, overhead cross piece 17 with its deep groove or recess 19 along the under face, and the removable base 23 at the bottom with a shallow groove 26. The panel consists of a frame 43 having four sides and in some instances, an intermediate cross piece 44. In the lower space a solid panel of ply wood 45 is accommodated, while in the upper space a glass panel 46 is usually mounted although it too may be solid and made of plywood. The width of the frame 43 corresponds substantially with the distance between posts 11, but the length is slightly longer than the dimension between the top of the base 23 and the bottom line of the cross piece 17. To insert the panel 39, reference is made particularly to Figure 1 which shows the manner of installation, wherein the upper or top side of the frame 43 is rested against the mouldings 20, while the lower end of the frame is supported from below and then pushed upwardly until the upper side of the frame is inserted well into the recess 19 of the cross piece 17. At this point the frame is swung inwardly until the same is aligned with the posts, the lower side of the frame 43 being clear of the upper line of the base 23 because of the depth at which the top of the frame seats in the recess 19. By withdrawing the support, the frame 43 is allowed to ride downwardly until the bottom rests on the bottom of the groove 26. The lowered position of the frame 43 is not sufficient to free the upper side from the sides of the upper channel 19 so that the entire panel 39 is firmly supported from above and below against falling out of the partition. To complete the installation the separable strips of moulding 21 are placed in position and securely fastened in the posts.

Inasmuch as the moulding strips 21 are removable, it is contemplated to imbed in the side of the post adjacent the panel a U-shaped spring metal strip 47 which is provided with spaced openings 48 to accommodate nails or screws 49, see Figure 20.

To substitute a door for a fixed panel it is simply necessary to remove the moulding 21 and take out the panel. If the back moulding 20 as shown in Figure 6 is separable, it too is simply removed, but if it is a part of the post 11 it must be cut away to leave a smooth clear face to receive a door jam 50, as illustrated in Figure 5, which consists of a flat strip having a moulding or stop bead 51 along the one edge, against which

the door closes. If sectional unit is again required, the moulding 20 which has been cut away may be replaced by a loose moulding strip. In order to clear the floor for a sill 52, the floor strip 10 is cut away between the posts. The door 40 is hung in the usual manner upon hinges 53 carried by one of the jam pieces 50.

The space above the cross piece 17 receives a fixed light 41 in very much the same manner as that used to install the panel, the frame 54 of the light being raised into the groove 15 and then lowered onto the upper surface of the cross piece, as illustrated in Figure 3. In order to substitute the pivoted transom 42 for the fixed unit, it is not necessary to cut away any of the moulding 20, a strip 55 being used to fill in the space between the inside face of the moulding 20 and the opposite edge of the post. This strip on each upright side carries the pivot hardware 56. The upper rail 57 of the transom frame is rabbeted and abuts a rabbeted strip 58 which has been mounted in the upper recess 15. It will be noted that the upper sash or fixed light frame is readily removed and a pivoted sash substituted therefor without any structural change being made in the skeleton frame. The transom in turn is just as readily removed to be replaced by a fixed sash. This is of considerable importance because it is the overhead transom installation which requires more changes than any other portion of a partition of this character.

In some instances, the posts 11 are held to the floor strip 10 by either a regular angle iron 59 or a specially constructed iron 60 illustrated for example in Figures 11 and 12, which consists of an angle iron having one arm fastened on the floor strip 10 while the upright arm is fastened to the post and is provided with a slit 61, the opposite walls of which are beveled outwardly towards the post. The base board at the end of each tongue 24 is provided with a beveled strip 62 which slides into the slot 61 of the iron 60 and prevents any spreading of the posts at their lower ends.

Due to the practical construction of the partition, its ease and simplicity in dismantling and re-erection into any form and location and because of the very few different parts, the maintenance cost is much less than with any other type of partition.

Another practical form of the present invention is shown in Figures 13 and 14 which illustrate a bank screen consisting of the upright posts or pilasters 11 and cross pieces 17, but without the upper rail. The arrangement of the base and the lower panel is identical with the construction already described, but without the anchorage at the upper ends of the posts. The screen would be very insecure if it were not for the rods 30 which give the required rigidity to the entire structure without sacrificing any of its attractiveness or utility.

In Figure 8, I have illustrated the assembly of my partition when a corner section is required as well as when a dividing section has been installed. The post 11 at the corner on its outer side receives a strip 63, which is set against either a fixed or removable moulding strip 20 or 21 respectively, and which projects beyond the adjacent face of the post to form one wall of a channel, the other wall being formed by a removable moulding strip 64. The intermediate dividing partition is erected by adding a carrying strip 65 to the face of the post. The face of the strip 65 is flat except along one side which is provided with

a moulding 66 forming one wall of a channel receiving a panel, the other wall comprising a separable moulding strip 67. The inner face of the carrying strip 65 is substantially U-shaped so as to embrace the corners of the post.

Figure 15 illustrates a construction embodying extra upper light section or sections 68, which while the light itself is the same in construction and assembly as that described in connection with the single section in Figure 3, it does require an extension post 69 for the upper ends of the post 11. Each section or extension post 69 is held rigidly in upright position above its post 11 by means of a rail bolt 70 which screws into a flanged socket 71 mounted upon the upper end of the post 11 and runs through a bore 72 in the latter and the extension. The free end of the bolt 70 projects into a recess 73 in the extension post 69 and receives a nut 74 to draw downwardly upon the extension when tightened and form a rigid union between the two parts. A second or upper header 75 is then mounted at its ends against the inner faces of the extension posts 69 in the same manner as described for the lower header 17. A cover strip 76 is applied to the extension post 69 and header strip 17 to conceal the meeting line of the latter and post 11 and the rough exterior of the upper header strip 13. If the ceiling line is particularly high, another extension post 69 is installed in the same way and the crown moulding strips 14 which would ordinarily be mounted on the header 13 are carried by the uppermost header strip 77.

Having now described my invention and the manner in which the same is used, what I claim and desire to secure by Letters Patent is:

1. A partition of the character described, comprising a plurality of spaced upright posts, cross pieces arranged between the posts and provided with longitudinal grooves in their under sides, a removable base piece for the space between adjacent posts, the upper face of the base being provided with a longitudinal groove, and a panel insertable between the posts and of a length to allow it to first be lifted so that the upper end enters the groove in the cross piece and the lower end is movable over the base and lowered into the groove in the base without being entirely free of the groove in the cross piece.

2. A partition, as claimed in claim 1, including moulding strips arranged on opposite sides of the inner face of each post to hold the upright sides of the panel in position.

3. A partition, as claimed in claim 1, including flanged strips attached to the inner faces of the posts above the cross piece, a rabbeted piece at the upper ends of the posts, and a pivoted transom mounted between the flanged strips and having a rabbeted upper rail to meet the first rabbeted piece.

4. A partition, as claimed in claim 1, including a top strip mounted on the upper ends of the posts and provided with a longitudinal groove in its under face, and a sash inserted along its upper side into said groove and then let down to rest upon the upper face of the cross piece without freeing its upper side from the groove.

5. A partition of the character described, comprising a plurality of spaced upright posts, each thereof comprising a plurality of superimposed sections provided with longitudinal openings and transverse recesses, means disposed longitudinally of the openings in said sections to attach one section to another, and fastening means for each

- post comprising a bolt threaded at its ends and projecting into recesses in the adjacent posts, and a nut adjustable over each end of the bolt and against the wall of the recess to draw and rigidly hold the sections of the post together.
6. A partition, as claimed in claim 1, including a moulding strip attached to the inner face of a post to form an intermediate partition comprising a flat strip provided with a U-shaped inner wall to embrace the post and project about two corners thereof, a moulding along its outer face to form a stop for a panel, and another removable moulding strip to abut the opposite side of the panel.
10. 7. A partition, as claimed in claim 1, including a moulding strip attached to the outside face of a post to form a corner partition, said strip hav-

ing a moulding projecting parallel to and beyond the corner of the post to form a stop for one side of a panel projecting at an angle to the main portion of the partition, and a removable moulding strip attachable to the face of the post and abutting the other side of the panel.

8. A partition of the character described, comprising upright posts, each thereof having its opposite walls provided with longitudinally disposed recesses adjacent and parallel to the corners and moulding strips mounted in said recesses to form channels to receive panel sections, and spring metal members arranged in the recesses to embrace the portions of the mouldings projecting into the recesses.

HARRY A. WALDMAN.
